DANCING FIGURE TOY

Daniel B. Swayze, Newark, N. J.

Application March 2, 1946, Serial No. 651,446

3 Claims. (Cl. 46—137)

1

This invention relates to a novel construction of dancing figure toy adapted for easy manipulation by a child whereby to afford pleasing amusement.

The invention has for an object to provide a toy of the kind mentioned comprising a casing, a jointed figure supported exteriorly from the casing, an exterior vibratory platform below the figure, and mechanism within the casing for vibrating said platform; said casing having a hand grip portion of the pistol grip type, and a pivoted trigger member, in finger engageable relation to said hand grip portion, which is manipulatable to actuate the platform vibrating mechanism.

Other objects of this invention, not at this time more particularly enumerated, will be understood from the following detailed description of the same.

An illustrative embodiment of this invention is shown in the accompanying drawings, in which—

Fig. 1 is a longitudinal sectional view of the dancing figure toy according to this invention; and Fig. 2 is a transverse vertical sectional view, taken on line 2—2 in Fig. 1.

Similar characters of reference are employed in the above described views, to indicate corresponding parts.

Referring to the drawings, the reference character 10 indicates a casing which may be made of sheet metal, molded plastic, or other suitable material. Said casing is, as to its general form, of pistol-like shape, comprising a barrel portion 11 having at its rearward end a hand grip portion 12 of the pistol grip type. Rearwardly of the forward extremity of the barrel portion 11, and adapted to depend therefrom, are laterally spaced side or bracket plates 13.

Fixed to and between said side or bracket plates 13 is a transverse shaft 14. Rotatably supported on said shaft 14, by its hub 15, is a segmental driving gear 16. Also fixed to and between said side or bracket plates 13 is another transverse shaft 17 which is suitably spaced below said driving gear 16. Rotatably mounted on said shaft 17, by its hub 18, is a driven gear 19 which is in mesh with said driving gear 16.

Fixed on the hub 18 of said driven gear 19, so as to turn therewith, is a crank-wheel 20. Pivotedly coupled to said crank-wheel 20, by the crank pin portion 21 with which its lower end is provided, is a reciprocable rod 22, the upper end portion of which slidably extends through an opening 23 in the top of the casing. Affixed to

the exteriorly projecting upper end of said reciprocable rod 22 is a horizontal platform 24.

Affixed by its lower end to the top of said casing is an upstanding supporting rod or standard 25, which extends through an opening 25' in said platform 24. Connected with the upper end of said supporting rod or standard 25, so as to be immovably supported thereby, is the body portion 26 of a dancing figure of any suitable design. Joined to the lower part of said fixed body portion 26 of the figure are a pair of articulated leg members 27 adapted to depend therefrom and over the vibratory platform 24. The articulation of said leg members 27 may be arranged in any suitable manner, but preferably includes a pivoting hip joint 28 and a pivoted knee joint 29, whereby movements in simulation of dance steps may be imparted to the leg members by the vibratory platform, as will hereinafter more particularly appear. Pivotedly attached to the upper part of the fixed body portion 26 of the figure are a pair of arm members 30.

Affixed to a side or bracket plate 13, to project inwardly therefrom behind the driving gear 16 is a stop projection or pin 31 adapted to be abutted by the rear edge 16' of said driving gear. Anchored within the casing 10, behind said driving gear 15, is a pull spring 32, which is attached by its forward end to said driving gear 16, whereby to yieldably hold the latter stopped against clockwise movement, by abutment against stop projection or pin 31.

Manipulatable means is provided for actuating the driving gear 16. This means comprises a trigger member 33, which is fulcrumed on a cross-pin 34 that is affixed to and within the barrel portion 11 of the casing forwardly of the hand grip portion 12 thereof. Said trigger member 33 is preferably of curvilinear shape terminating in a forwardly projecting free end portion 35. Connected between the free end portion 35 of said trigger member and the lower part of said driving gear 16 is a link 36. Said side or bracket plates 13 are spaced forwardly apart from the hand grip portion 12 of the casing 10, whereby to provide what may be termed an intermediate finger guard space 37, across which said trigger member 33 extends so as to be exposed to engagement by a finger of the hand by which the hand grip portion 12 is grasped for holding the toy. When the toy is grasped by the hand grip portion 12, and the trigger member 33 engaged by a finger of the grasping hand, the mechanism may be actuated to cause dancing movement of the figure. This is accomplished by alternately pulling

and releasing said trigger member. When the trigger member is pulled, the backward swing thus imparted thereto is transmitted through the link 36 to the driving gear 16, whereby to impart limited counterclockwise motion thereto against the tension of the pull spring 32. Such motion of the driving gear is transmitted to the driven gear 19, whereby to impart limited clockwise motion thereto and to the crank-wheel 20. Such motion of the crank wheel 20 produces an upward movement of the rod 22 and platform 24, whereby the latter kicks against the jointed leg members 27 of the figure, and thereby causes simulated dance-step upward movements of the latter. When the trigger member 33 is released, the pull spring 32 produces the reverse of the described movements of the driving gear, driven gear, crank-wheel and reciprocable rod 22 and platform 24, thus causing the latter to descend, so that gravity may cause downward movements of the leg members 27 of the figure. It will thus be obvious that repeated alternate pull and release of the trigger member 33 will, through the described actuating mechanism, cause a vertical vibration of the platform 24 relative to the jointed leg members of the figure which are suspended thereover, and consequently by the intermittent contact of the former with said leg members, will toss the same upward, whereby to cause simulation of very life-like dance step movements thereof. At the same time, the above described movements of the leg members will cause such swaying vibration of the body 26 as will be sufficient to induce some accompanying swinging movements of the pivoted arm members 30 of the figure, and thus enhance the dance simulating movements of said figure as a whole.

Having now described my invention, I claim:

1. A dancing figure toy comprising in combination a pistol-shaped casing, a jointed figure supported exteriorly from said casing by means attached to said casing, an exterior platform below said figure, vertically reciprocable means for supporting said platform, a crank-wheel mounted within said casing for reciprocating said latter means, gearing also mounted within said casing for actuating said crank-wheel, said casing having a hand grip portion of the pistol grip type, a pivoted trigger member in finger engageable relation to said hand grip portion, and a link interconnecting the free end portion of said trigger member with said gearing, whereby movement of said trigger member actuates said gearing.

2. A dancing figure toy comprising in combination a pistol-shaped casing having a barrel por-

tion terminating at its rearward end in a hand grip portion of the pistol grip type, said barrel having laterally spaced opposed side plates dependent therefrom and spaced forwardly of said hand grip portion, intermeshing driving and driven gears mounted between said side plates, a crank-wheel rotatable with said driven gear, a reciprocable rod actuated by said crank-wheel having its upper end projecting exteriorly of the casing barrel, a platform carried by the exterior end of said rod, a jointed figure, means attached to said casing to support said figure over said platform, a trigger member pivotally connected to said casing barrel and accessibly disposed intermediate said side plates and hand grip portion and in finger engageable relation to the latter, and a link interconnected between said trigger member and said driving gear, whereby motion of the former is transmitted to the latter.

3. A dancing figure toy comprising in combination a pistol-shaped casing having a barrel portion terminating at its rearward end in a hand grip portion of the pistol grip type, said barrel having laterally spaced opposed side plates dependent therefrom and spaced forwardly of said hand grip portion, intermeshing driving and driven gears mounted between said side plates, a crank-wheel rotatable with said driven gear, a reciprocable rod actuated by said crank-wheel having its upper end projecting exteriorly of the casing barrel, a platform carried by the exterior end of said rod, a jointed figure, means attached to said casing to support said figure over said platform, a trigger member pivotally connected to said casing barrel and accessibly disposed intermediate said side plates and hand grip portion and in finger engageable relation to the latter, and a link interconnected between said trigger member and said driving gear, whereby motion manually imparted to the former produces movement of the latter in one direction, and spring means for producing movement of said driving gear and trigger member in the opposite direction.
